US0D1074633S

(12) **United States Design Patent** (10) **Patent No.:** **US D1,074,633 S**
(45) **Date of Patent:** **** May 13, 2025**

(54) **SMART PHONE**

(71) Applicant: **Lenovo (Beijing) Limited**, Beijing (CN)

(72) Inventors: **Jingjia Li**, Beijing (CN); **Shasha Dong**, Beijing (CN)

(73) Assignee: **Lenovo (Beijing) Limited**, Beijing (CN)

(**) Term: **15 Years**

(21) Appl. No.: **35/519,387**

(22) Filed: **Aug. 21, 2023**

(80) **Hague Agreement Data**

Int. Filing Date: **Aug. 21, 2023**

Int. Reg. No.: **DM/233679**

Int. Reg. Date: **Aug. 21, 2023**

Int. Reg. Pub. Date: **Dec. 15, 2023**

(30) **Foreign Application Priority Data**

Feb. 21, 2023 (CN) 202330064229.1

(51) **LOC (15) Cl.** **14-03**

(52) **U.S. Cl.**

USPC ..... **D14/138 C**; D14/248
